UNITED STATES PATENT OFFICE

HARRY G. MOORE, OF LOS ANGELES, CALIFORNIA

INLAID ART MATERIAL AND PROCESS FOR MANUFACTURING THE SAME

Application filed August 5, 1930, Serial No. 473,251. Renewed April 8, 1933.

This invention relates to an improved inlaid art material and the process for manufacturing the same, and has for one of its principal objects the provision of an art material which can be used for various purposes and which embodies a surface of felt or similar material, having imbedded therein and incorporated therewith one or more of a series of inlays, preferably of the same 5 felt material, but of different colors, whereby an attractive decorative inlay is produced.

One of the important objects of this invention is the provision of an inlaid art material composed of felt or similar cloth or some other material, and which can be used for articles of clothing, pennants, and even for decorative purposes in buildings or the like, and which is capable of many modifications and variations, while at the same 15 time affording a simple yet quite effective and ornamental device.

Still another and further important object of the invention is the provision in a decorative art material of felt or the like, having a background of a waterproof cloth or similar composition, the felt being in sections inlaid in each other and attached to the waterproof or other background by a 25 suitable cement and pressure whereby a unitary finished article is produced which is not liable to come apart even under severe usage.

Other and further important objects of 30 the invention will be apparent from the disclosures in the accompanying drawing and the following specification.

The invention, in a preferred form, is shown in the drawing and hereinafter more 35 fully described.

In the drawing:

Figure 1 is a plan view of the inlaid art material of this invention showing a representative design.

Figure 2 is a sectional view on the line 40 2-2 of Figure 1.

As shown in the drawing:

The reference numeral 10 indicates generally a piece of felt or similar material 45 which has an opening cut thereinto by

means of a die or the like, which opening may be of any size or shape. In this opening is fitted a correspondingly-shaped inlay 12 which, in itself, has another opening cut therein, this opening being filled by another 55 inlay 14 of perhaps a different shape and also of a different color.

Another opening is formed in the member 14, and in this is fitted an inlay 16, which itself is similarly apertured, and a further inlay 18 is fitted therewith, this in turn having another opening into which is fitted a still further inlay 20. Obviously, 60 the number of inlays is limited only by the capacity of the original sheet. 65

It has been found in practice that when using a die of one size to cut both the background material and the inlay material, the resultant product is not nearly as satisfactory as regards evenness of surface and close fitting, as when a die of one size is used for perforating the background and a die of slightly larger size used to stamp out the inlay material. Use of the latter method 70 or process results in a much better and closer 75 fitting and positioning of the parts.

After the inlays have been cut out and positioned, each inlay preferably being of a contrasting color from the adjacent inlay, they are placed in their proper position 80 upon a backing or base 22 of a pliable material, which is preferably waterproof, this having been previously coated on its upper face with a suitable adhesive, such as casein 85 glue or the like.

The complete section is then turned so that the felt is on the bottom, and placed in a press for a suitable period of time, and a suitable amount of pressure applied thereto, the pressure being approximately 90 two tons. In this manner, the glue is forced into the interstices between the inlay sections and also soaks into the felt, so as to provide in the finished article a very excellent cemented job. 95

It will be evident that the shapes and sizes of the inlays may be changed throughout practically an infinite range, and that the color combinations may be also accordingly varied, so as to produce substantially 100

any desired result or pattern. Further, the material itself, both of the inlays and their background, and also of the backing or base, may be changed considerably without effecting the product and the process of the invention. It is also found that pre-shrinking the material of the inlays before their insertion into the background is desirable, as a more even surface of the finished product accordingly results.

15 I am aware that many changes may be made and numerous details of construction varied throughout a wide range without departing from the principles of this invention, and I, therefore, do not purpose limiting the patent granted hereon otherwise than as necessitated by the prior art.

I claim as my invention:

20 1. A process of manufacturing an inlaid art material, comprising the cutting of an opening in a background of felt, placing an inlay of slightly larger but similar shape and material in the opening, and fastening the background and inlay upon a base of 25 pliable waterproof material by compression.

30 2. A process of manufacturing an inlaid art material, comprising the cutting of an opening in a background of felt, placing an inlay of slightly larger but similar shape and material in the opening, and gluing the background and inlay upon a base of 35 pliable waterproof material with waterproof glue material.

35 3. In the manufacture of an inlaid art material, comprising a background of cloth, the cutting of openings in the background with a die, and the stamping out of inlay material for the opening with a die of the same shape, but of slightly larger size.

40 4. In the manufacture of an inlaid art material, comprising a background of cloth, the cutting of openings in the background with a die, and the stamping out of inlay 45 material for the opening with a die of the same shape, but of slightly larger size, all of the inlay material having been previously shrunk.

45 5. An inlaid art material, including a background of felt, a plurality of inlays of similar material of various shapes and colors in the background, said inlays being originally of greater thickness than the background.

50 6. An inlaid art material, including a background of felt, a plurality of inlays of similar material of various shapes and colors in the background, said inlays being originally of greater thickness than the background, but compressed to the same thickness as the background when inserted therein.

55 7. An inlaid art material, including a background of felt, a plurality of inlays 60 of similar material of various shapes and

colors in the background, said inlays being originally of greater thickness than the background, and a backing for the whole.

8. An inlaid art material, including a background of felt, a plurality of inlays of 70 similar material of various shapes and colors in the background, said inlays being originally of greater thickness than the background, and a backing for the whole, together with cement for fastening the inlays 75 and background to the backing.

9. An inlaid art material, including a background of felt, an inlay of similar material but of a different color mounted in the background, said inlay being originally 80 of greater thickness than the background.

10. An inlaid art material, including a background of felt, an inlay of similar material but of a different color mounted in the background, said inlay being originally of 85 greater thickness than the background but compressed to the same thickness as the background when inserted therein.

11. A process of manufacturing an inlaid art material, comprising the cutting of an 90 opening in a background of felt, placing in the opening an inlay of similar shape but originally of greater thickness and compressed to the thickness of the background, and fastening the background and inlay 95 upon a base of pliable material.

12. In the manufacture of an inlaid material comprising a background of felt, the cutting of openings in the background with a die and the stamping out of an inlay material of felt for the opening with a die of the same shape and size and the shrinking of the inlay material previous to its insertion.

13. In testimony whereof I affix my signature:

HARRY G. MOORE.
